DESIGN FOR WALL-PAPER.

SPECIFICATION forming part of Design No. 22,847, dated October 24, 1893.

Application filed September 19, 1893. Serial No. 485,912. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of ornaments of the French renaissance style with festoons formed of small bell-shaped ornaments as represented in the accompanying drawing. The figures are placed at regular distances apart over the surface of the paper. Similar shaped ornaments and festoons connected and ar-

ranged above horizontal lines form the border for said design as shown in the accompanying drawing.

What I claim is—

1. The design for wall paper herein shown and described.
2. In the design for wall paper the border herein shown and described.

Witness my hand this 15th day of September, 1893.

CHARLES BOOZE.
